FIG. 1

FIG. 2

FIG. 3

FIG. 4

FIG. 5

FIG. 6

FIGURE 1 is a perspective view of a spectacle case showing my new design;

FIGURE 2 is a side elevational view thereof;

FIGURE 3 is one end elevational view thereof;

FIGURE 4 is another end elevational view thereof;

FIGURE 5 is a bottom plan view thereof; and

FIGURE 6 is a top plan view thereof.

My design for the spectacle case disclosed is characterized by the appearance presented by the combination of the dual fold, comprising one side of the said case, with the straight edge portions in flattened condition on the opposite side thereof, in association with the remaining features as shown.

I claim:

The ornamental design for a spectacle case, substantially as shown and described.
